The ornamental design for a payment card with sensor, as shown and described.

DESCRIPTION

FIG. 1 is a front side perspective view of a first embodiment of a payment card with sensor showing our new design;

FIG. 2 is a front side view thereof;

FIG. 3 is a back side view thereof;

FIG. 4 is a top elevational view thereof;

FIG. 5 is a bottom elevational view thereof;

FIG. 6 is a left side elevational view thereof;

FIG. 7 is a right side elevational view thereof;

FIG. 8 is a front side perspective view of a second embodiment of a payment card with sensor showing our new design;

FIG. 9 is a front side view thereof;

FIG. 10 is a back side view thereof;

FIG. 11 is a top elevational view thereof;

FIG. 12 is a bottom elevational view thereof;

FIG. 13 is a left side elevational view thereof;

FIG. 14 is a right side elevational view thereof;

FIG. 15 is a front side perspective view of a third embodiment of a payment card with sensor showing our new design;

FIG. 16 is a front side view thereof;

FIG. 17 is a back side view thereof;

FIG. 18 is a top elevational view thereof;

FIG. 19 is a bottom elevational view thereof;

FIG. 20 is a left side elevational view thereof;

FIG. 21 is a right side elevational view thereof;

FIG. 22 is a front side perspective view of a fourth embodiment of a payment card with sensor showing our new design;

FIG. 23 is a front side view thereof;

FIG. 24 is a back side view thereof;

FIG. 25 is a top elevational view thereof;

FIG. 26 is a bottom elevational view thereof;

(Continued)

FIG. 27 is a left side elevational view thereof;
FIG. 28 is a right side elevational view thereof;
FIG. 29 is a front side perspective view of a fifth embodiment of a payment card with sensor showing our new design;
FIG. 30 is a front side view thereof;
FIG. 31 is a back side view thereof;
FIG. 32 is a top elevational view thereof;
FIG. 33 is a bottom elevational view thereof;
FIG. 34 is a left side elevational view thereof;
FIG. 35 is a right side elevational view thereof;
FIG. 36 is a front side perspective view of a sixth embodiment of a payment card with sensor showing our new design;
FIG. 37 is a front side view thereof;
FIG. 38 is a back side view thereof;
FIG. 39 is a top elevational view thereof;
FIG. 40 is a bottom elevational view thereof;
FIG. 41 is a left side elevational view thereof;
FIG. 42 is a right side elevational view thereof;
FIG. 43 is a front side perspective view of a seventh embodiment of a payment card with sensor showing our new design;
FIG. 44 is a front side view thereof;
FIG. 45 is a back side view thereof;
FIG. 46 is a left side elevational view thereof;
FIG. 47 is a right side elevational view thereof;
FIG. 48 is a top elevational view thereof;
FIG. 49 is a bottom elevational view thereof;
FIG. 50 is a front side perspective view of an eighth embodiment of a payment card with sensor showing our new design;
FIG. 51 is a front side view thereof;
FIG. 52 is a back side view thereof;
FIG. 53 is a left side elevational view thereof;
FIG. 54 is a right side elevational view thereof;
FIG. 55 is a top elevational view thereof;
FIG. 56 is a bottom elevational view thereof;
FIG. 57 is a front side perspective view of a ninth embodiment of a payment card with sensor showing our new design;
FIG. 58 is a front side view thereof;
FIG. 59 is a back side view thereof;
FIG. 60 is a left side elevational view thereof;
FIG. 61 is a right side elevational view thereof;
FIG. 62 is a top elevational view thereof;
FIG. 63 is a bottom elevational view thereof;
FIG. 64 is a front side perspective view of a tenth embodiment of a payment card with sensor showing our new design;
FIG. 65 is a front side view thereof;
FIG. 66 is a back side view thereof;
FIG. 67 is a left side elevational view thereof;
FIG. 68 is a right side elevational view thereof;
FIG. 69 is a top elevational view thereof;
FIG. 70 is a bottom elevational view thereof;
FIG. 71 is a front side perspective view of an eleventh embodiment of a payment card with sensor showing our new design;
FIG. 72 is a front side view thereof;
FIG. 73 is a back side view thereof;
FIG. 74 is a left side elevational view thereof;
FIG. 75 is a right side elevational view thereof;
FIG. 76 is a top elevational view thereof;
FIG. 77 is a bottom elevational view thereof;

FIG. 78 is a front side perspective view of a twelfth embodiment of a payment card with sensor showing our new design;
FIG. 79 is a front side view thereof;
FIG. 80 is a back side view thereof;
FIG. 81 is a left side elevational view thereof;
FIG. 82 is a right side elevational view thereof;
FIG. 83 is a top elevational view thereof;
FIG. 84 is a bottom elevational view thereof;
FIG. 85 is a front side perspective view of a thirteenth embodiment of a payment card with sensor showing our new design;
FIG. 86 is a front side view thereof;
FIG. 87 is a back side view thereof;
FIG. 88 is a top elevational view thereof;
FIG. 89 is a bottom elevational view thereof;
FIG. 90 is a left side elevational view thereof;
FIG. 91 is a right side elevational view thereof;
FIG. 92 is a front side perspective view of a fourteenth embodiment of a payment card with sensor showing our new design;
FIG. 93 is a front side view thereof;
FIG. 94 is a back side view thereof;
FIG. 95 is a top elevational view thereof;
FIG. 96 is a bottom elevational view thereof;
FIG. 97 is a left side elevational view thereof;
FIG. 98 is a right side elevational view thereof;
FIG. 99 is a front side perspective view of a fifteenth embodiment of a payment card with sensor showing our new design;
FIG. 100 is a front side view thereof;
FIG. 101 is a back side view thereof;
FIG. 102 is a top elevational view thereof;
FIG. 103 is a bottom elevational view thereof;
FIG. 104 is a left side elevational view thereof;
FIG. 105 is a right side elevational view thereof;
FIG. 106 is a front side perspective view of a sixteenth embodiment of a payment card with sensor showing our new design;
FIG. 107 is a front side view thereof;
FIG. 108 is a back side view thereof;
FIG. 109 is a left side elevational view thereof;
FIG. 110 is a right side elevational view thereof;
FIG. 111 is a top elevational view thereof;
FIG. 112 is a bottom elevational view thereof;
FIG. 113 is a front side perspective view of a seventeenth embodiment of a payment card with sensor showing our new design;
FIG. 114 is a front side view thereof;
FIG. 115 is a back side view thereof;
FIG. 116 is a left side elevational view thereof;
FIG. 117 is a right side elevational view thereof;
FIG. 118 is a top elevational view thereof;
FIG. 119 is a bottom elevational view thereof;
FIG. 120 is a front side perspective view of an eighteenth embodiment of a payment card with sensor showing our new design;
FIG. 121 is a front side view thereof;
FIG. 122 is a back side view thereof;
FIG. 123 is a left side elevational view thereof;
FIG. 124 is a right side elevational view thereof;
FIG. 125 is a top elevational view thereof; and,
FIG. 126 is a bottom elevational view thereof.

The broken lines in the drawings depict portions of the payment card that are not part of the claimed design. Structures drawn in broken lines are included for the purpose of showing the design in a condition of use. None of the broken line structures and features they depict form part of the claimed design.
